CLAIM

The ornamental design for an apron front sink as shown and described.

DESCRIPTION

FIG. 1 is a front perspective view of the claimed design; FIG. 2 is a rear perspective view of the design of FIG. 1; FIG. 3 is a front view of the design of FIG. 1; FIG. 4 is a rear view of the design of FIG. 1; FIG. 5 is a side view of the design of FIG. 1; FIG. 6 is another side view of the design of FIG. 1; FIG. 7 is a top view of the design of FIG. 1; and, FIG. 8 is a bottom view of the design of FIG. 1.

The ornamental design which is claimed is shown in solid lines in the drawings. The broken lines in the drawings are for illustrative purposes only and form no part of the claimed design. For example, broken lines formed by equal length dashes show unclaimed portions of the design. Cross-hatching provided on cut surfaces is for illustrative purposes only and forms no part of the claimed design.

1 Claim, 7 Drawing Sheets
